UNITED STATES PATENT OFFICE.

ABRAHAM NOVICK, OF NEW YORK, N. Y., ASSIGNOR TO F. L. SCHMIDT COMPANY, OF NEW YORK, N. Y., A CORPORATION OF NEW YORK.

ENVELOP-FASTENER.

1,358,234.

Specification of Letters Patent.

Patented Nov. 9, 1920.

Application filed September 26, 1916. Serial No. 122,190.

To all whom it may concern:

Be it known that I, ABRAHAM NOVICK, a citizen of the United States, of the city of New York, county and State of New York, have invented certain new and useful Improvements in Envelop-Fasteners, of which the following is a specification.

This invention relates to envelop fasteners for holding closed the flap of an envelop.

The object of this invention is to provide a fastener or clasp that is inexpensive both in its construction and method of applying it to an envelop. Further objects are to avoid the use of exposed metal and to provide a fastener that can be supplied to the envelop maker in the form of a reel of tape properly prepared for forming and attaching to envelops.

Referring to the accompanying drawings Figure 1 is a view of an envelop with my fastener in its preferred form, single tongue type. Fig. 2 shows the same fastener with the flap closed. Fig. 3 shows the same fastener enlarged. Fig. 4 shows the same type of fastener modified so as to form a double tongue fastener. Fig. 5 shows it holding a flap closed. Fig. 6 shows it enlarged. Fig. 7 shows another modification of the same fastener as in Figs. 1, 2 and 3. Fig. 8 is a detail view of the fastener tape or material before forming and attaching. Fig. 9 is a section on line A. A. of Fig. 8.

In the preferred embodiment of my invention the fastener material comprises a strip of sheet material 1, which may be of paper, cloth or some other suitable stock. This strip is provided with an adhesive 2 on one face thereof. A metal strip 3, preferably materially narrower than strip 1, has folded thereabout a second strip of sheet material 13 and said second strip may inclose said metal strip 3. Preferably said second strip 13 is approximately twice the width of said metal strip and has its lateral edges folded over the edges of the metal strip thereby incasing said metal strip. Then said second strip 13, inclosing said metal strip, is laid lengthwise and preferably positioned midway widthwise said first strip 1, with the faces of the adjoining edge portions of said second strip 13 contacting with and secured to said first strip 1 by adhesive 2. There is thereby provided a strip of envelop fastener material as shown in Figs. 8 and 9 adapted to be supplied to the

envelop manufacturer. For forming individual fasteners, a short portion is severed from the strip of fastener material of Fig. 8, see Fig. 3; and that portion of strip 1 to which strip 13 is attached, the widthwise mid-portion in Fig. 3, is separated near one end thereof from the laterally adjoining portion or portions 11 and 12 by cuts or incisions 4, 4. Preferably these incisions extend from one half to two thirds the length of the short portion of Fig. 3. There is thereby formed a prong or tongue 5, comprising a portion of strip 1, a portion of folded strip 13 and a portion of metal strip 3. The gummed surface 2 is then moistened and applied to the envelop as in Fig. 1, the prong 5 being bent up and passed through the flap hole 6 and then bent over until flat as in Fig. 2.

Fig. 6 shows a fastener of the double tongue type made up of the strip of fastener material of Fig. 8 by cutting a portion therefrom and making four cuts 10 therein, then applying it to the envelop as in Fig. 4. The two tongues 7 and 8 are then raised and passed through the flap hole 9 and bent back again as in Fig. 5.

The fastener shown in Fig. 7 is made similar to the one shown in Fig. 3 except that the side portions 11 and 12 are cut away.

Claims:

1. An envelop fastener including in combination a strip of sheet material having an adhesive on one face, a strip of metal narrower than said strip of sheet material, and a second strip of sheet material folded about said metal strip, said second strip of sheet material, carrying said metal strip, being laid lengthwise said first strip of sheet material and secured thereto by said adhesive, that portion of said first strip of material, to which said folded second strip is attached, being separated near the end from the laterally adjoining portion thereof whereby a tongue, comprising an end portion of said first strip, an end portion of said second strip and an end portion of said metal strip, is formed.

2. An envelop fastener including in combination a strip of sheet material having an adhesive on one face, a strip of metal narrower than said strip of sheet material laid lengthwise and positioned midway widthwise said strip of sheet material, and inclos-

ing means for attaching said metal strip to said strip of sheet material, that midportion of said strip of material to which said metal strip inclosing means is attached being separated near the end from the laterally adjoining portions thereof, whereby a widthwise centrally located inclosed tongue is formed.

3. An envelop fastener including in combination a strip of sheet material having an adhesive on one face, a strip of metal incased for its whole length in another strip of material, said incasing strip of material being attached to said first strip of material 15 by the adhesive thereon, said first strip of

material being of greater width than said incased strip of metal and slotted near its end, adjacent said incased metal strip, to permit the end of said incased metal strip to be bent away from the adjacent body portion of said first mentioned strip when said body portion is attached by its adhesive to an envelop. 20

Signed at New York, this 20th day of September, 1916, in the presence of two subscribing witnesses. 25

ABRAHAM NOVICK.
